APPARATUS FOR DILUTING GAS

Harry Cleevely, Rankin, Pa.

Application August 9, 1930, Serial No. 474,273

3 Claims. (Cl. 48—184)

This invention relates to a method of utilizing liquefied or compressed gases, such as one of the highly volatile liquefied petroleum gases, for instance propane or a mixture of similar gases, which are normally put up in cylinders having suitable connections for conducting the gas from the cylinder to appliances where the vaporized gas is to be used. Because of the relatively small volume of liquid contained in these cylinders and the unnecessarily high heat value of the gas, the gas is too expensive to be used for ordinary domestic purposes as the average bottled gas costs the consumer approximately \$18 per 1,000 cubic feet and the heat value is too high to be realized with ordinary use and the average appliances to give any usefulness commensurate with the amount paid. It is possible, by the addition of air, or some other suitable diluent, to give a diluted gas, having a greater volume and a proportionately less B. t. u. value per cubic foot. The invention also relates to the utilization of gas formed by the expansion of previously compressed petroleum gas and which it is desired to dilute. The addition of this diluent or carbureting medium is usually accomplished by means of a mechanical device driven by some external force and it is one of the objects of the present invention to provide means for diluting gas under pressure and to use the gas pressure caused by the natural volatility of the gases when compressed to a liquid state to operate a device to inject into and mix with the rich gas the diluent in suitable proportions to produce the desired finished gas, or to use the pressure of a diluent to inject and mix with the diluent the gas desired to be used.

A further object is to provide a mechanism of this character which is operated automatically and in which the pressure of the vaporized liquefied or compressed gas will operate a pump, as it may be termed, causing the injection of air or other diluent into the stream of vaporized gas or use the pressure of the diluent for operating the pump as the case may be.

A further object is to provide a mechanism of this character which is particularly designed to secure a proper proportioning of a gas with a diluent and which is based on the principle of positive volumetric displacement or in other words by an apparatus of this character in which the proportioning of the two gases is secured by a simultaneous positive displacement of two volumes of the two gases in their correct proportions and the positive mixing or intermingling of these two gases in a common discharge pipe, the mechanism being such as to secure this positive proportioning by volume of the two gases.

Other objects will appear in the course of the following description.

My invention is illustrated in the accompanying drawings, wherein:

Figure 1 is an elevation of two gas tanks and showing my mechanism applied thereto;

Fig. 2 is a side elevation of one of the gas tanks on an enlarged scale showing my improved mechanism applied thereto;

Figure 3 is a vertical sectional view through the two diaphragm chambers of my apparatus and showing in elevation the allied mechanism;

Figure 4 is a vertical sectional view through the valve chamber and the valve therein, but the valve being shown in a different position from that shown in Figure 3.

The liquefied gas, as I have illustrated, is contained in the two tanks 10. If a commercial propane, as now on the market, is used, the product in the tanks has no pressure at 44° below zero, under which condition, it is liquid, 44° below zero being the boiling point of the gas. Therefore, at any temperature above 44° below zero, you must have it under pressure to keep it a liquid and as the temperature goes up, the pressure increases.

Thus at 32°, or freezing, there is about 45 lbs. pressure on the tank at 70° F. there is 125 pounds pressure and at 105° F., 225 pounds pressure, so that at all usual temperatures, that is, anything above 44° below zero, there will be a pressure due to the liquid trying to vaporize.

In ordinary installations, there is usually a gas storage tank containing the highly volatile liquid petroleum gas, also suitable connections for conducting the gas from the cylinder to the regular inlet and a suitable regulator for reducing the varying tank pressure to a constant outlet pressure for domestic use in conventional appliances.

Referring particularly to Figures 2 and 3, it will be seen that my apparatus is associated with a pressure reducing regulator 12 or like device (see Figure 1). This pressure regulator 12 may be of any suitable character and forms no part of my invention. From each of the tanks 10, leads a pipe 13, the entry of which is controlled by a valve 14 on the tank and these pipes 13 lead through manifold valves 15 to a manifold fitting 16 from which a pipe connection leads to the regulator 12. A pipe 11 leads from the regulator 12 and opens into a valve casing 17 of any suitable character shown as having therein a D-valve 18, the stem 19 of which extends out through the valve casing. The valve casing is formed with two discharge ports 20 and 21 and with a medially disposed port 22. The discharge ports 20 and 21 lead into a diaphragm casing designated generally 23 having therein a medially disposed diaphragm 24 of any suitable character and acting as a piston. This diaphragm separates the interior of the casing 23 into two chambers.

The pipe 21 opens into one of these chambers and the pipe 20 opens into the other chamber. The center of the chamber is formed with a stuffing box 25 through which the rod 26 passes which engages with the center of the diaphragm 24.

Disposed adjacent the diaphragm chamber 23 is a relatively large diaphragm casing 27 divided into two chambers by the relatively large diaphragm 28. Stud bolts 29 extend out from the casing 27 and support the casing 23. The casings 23 and 27 are each formed in two sections held together by bolts upon the respective diaphragms. The details of construction of these diaphragm chambers might be modified in many ways and the showing therefor is purely illustrative.

Entering each of the diaphragm chambers in the casing 27 are the inlet pipes 30, each having therein an upwardly opening valve 31, shown as check valves closing against pressure from within the diaphragm casing and opening when the pressure is reduced. Check valve casings 32 and 33 also open into two chambers of the casing 27 and discharge into a common pipe 34 which is connected by a T 35 to a pipe 36 leading from the port 22. Beyond the T 35 there is provided the discharge pipe 37 whereby diluted gas is carried to the point where it is to be used.

The diaphragm 28 is connected to the diaphragm 24 by means of the rod 26 which passes through stuffing boxes in the diaphragm casings 23 and 27 and which is connected to the center of the diaphragm 28.

For the purpose of operating the slide valve 18, I provide a lever 38 pivoted upon a bracket 39 and formed as illustrated with a fork 40 in the upper end of the lever. The stem 19 of the D-valve is shown as provided with two spaced studs 41.

Pivoted to a bracket 42 is a lever 43, the lower end of which is provided with a stud 44 operating within the fork 40 and operating between the two studs 41 as shown in Figures 3 and 4. A spring 45 is attached at its upper end to a stud 46 which is disposed immediately above the pivotal center of the lever 43, the lower end of the spring being attached to a stud 47 on the lever 43. The action of this spring, therefore, is to suddenly throw the lever in one direction or the other as the lever passes its dead center and thus the lever is very suddenly thrown from one of its positions to the other under the action of this spring after the lever has passed its dead center.

The operation of this mechanism is as follows:—Assuming that the slide valve 18 is in the position shown in Figure 3 in dotted lines, then the vaporized liquid discharged from either one of the tanks 10 passes down the pipe 11 and is discharged by means of the port 21 into the chamber on the right hand side of the diaphragm casing 23. This vapor being under high pressure acts to force the diaphragm 24 to the left in Figure 3 and force any gas that may be in the left hand chamber outward through the ports 28 and 22 into the pipe 36. The movement of the diaphragm 24 to the left in Figure 3 shifts the rod 26 toward the left and this shifts the diaphragm 28 toward the left. As the diaphragm shifts any air or other diluent contained within the left hand chamber 27 will be forced out through the check valve 33 into the pipe 34 and mixed with the gas discharged into the pipe 37 from the pipe 36. As the diaphragm 38 moves to the left in Figure 3, it will act to draw in a fresh supply of air through the inlet pipe and valve in the right

hand chamber so that this right hand chamber of the diaphragm casing 27 will fill with air while the air in the left hand chamber is being discharged.

As the rod 26 moves to the left in Figure 3 under pressure of the gas in the right hand chamber of casing 23, it will act to shift the lever 38 in the direction of the arrow in Figure 3. This will cause a movement of the lever 43 against one of the studs 41 in a direction to shift the slide valve 18 from the position shown in Figure 3 to that shown in Figure 4, but as the lever 43 passes beyond this center of motion, the spring 45 will cause the sudden and quick movement of the lever over to its position shown in Figure 4, thus causing a quick movement of the valve to the position shown in Figure 4. This will allow the gas to pass into the left hand chamber of the casing 23 and the diaphragm will move toward the right in Figure 3, forcing the gas accumulated in the right hand chamber out through the port 22 into the pipe 36 and causing the reverse movement of the diaphragm 28, forcing air out from the right hand chamber of the casing 27 and drawing air into the left hand chamber thereof. Thus, there will be a continuous and automatic oscillation of the connecting rod 26 and of the two diaphragms and the valve. It will be seen that with this mechanism, the gas under pressure acts as the motive power for a motor 23 whereby the air or other diluent is pumped into the stream of gas issuing from one or the other of the diaphragm chambers and that thus I provide means whereby the pressure of the liquefied or compressed gas is utilized for the purpose of pumping diluent thereinto, and that I do away with the necessity of using any extraneous pumping means operated by an extraneous motor.

This process differs from the present methods which may have been employed for diluting gaseous vapors in that it requires no external force for operation, making use of the pressure of the gas caused either by previous compression or due to the vapor pressure of the liquid gas or both to actuate the system.

The gas commonly used is propane, or butane, or a mixture of these or similar gases or liquids. These gases are liquefied and shipped as liquids for convenience, as one gallon propane equals 36 cubic feet of gas and one gallon of butane equals 32 cubic feet of gas. One cubic foot of propane contains two thousand, five hundred twenty-one B. t. u. and one cubic foot of butane, three thousand, two hundred and seventy-four B. t. u. and mixtures of these gases having a B. t. u. value in proportion to the percentage of the foregoing or other gases or liquids which may be used. The gas thus sold is used in places out of reach of manufactured or natural gas and is used extensively in houses. The gas can also be used to enrich leaner gas or when diluted can be piped to serve more than one home or outlet. Of course, piping such a needlessly high B. t. u. value gas which is quite expensive, is unprofitable, but in some cases, it is being done. Also by means of compressors or blowers equipped with proportioning devices to control the ratio of rich gas to the diluent, gas is now being piped in towns, factories, etc. However, usually it is common practice to use outside force such as electricity to operate the installation.

With the present liquefied petroleum or bottled gas installations, it is oftentimes impossible

to draw off the gas as fast as desired as by so doing the cylinder refrigerates, lowering the temperature of the liquid and hence preventing the vaporization of the liquid. This is generally overcome by making special installations of large size or by manifolding together smaller units both of which are expensive, not only in equipment investment, but in operating costs, so expensive as to be practically prohibitive.

10 In my system, this difficulty is practically eliminated, in the average installation due to the reduction of the rate of vaporization of the liquid in the cylinders.

15 My method and mechanism is particularly adapted for use with petroleum gas vaporizing from a liquid state that operates to decrease the B. t. u. value of one gas or increase the B. t. u. value of another or for mixing gases in desired proportions for any other purposes.

20 While my system will function as above described, particularly in the case of liquefied petroleum gas installations, it may also be used on gases which are under pressure due to more or less compression, such for instance, as natural 25 gas from a pipe line or from a tank and this pressure can be utilized for the operation of the system as previously mentioned. In other words, pressure may be either the natural pressure of the gas or what might be termed an artificial 30 pressure, that is, a gas which has been compressed.

While I have heretofore referred to the operation of the pumping diaphragm 28 by means of the pressure of gas on the motor diaphragm 24, I do not wish to be limited to this as the diluent may be under pressure and hence be used to operate the device. In this case, the diluent gas is passed to one side or the other of the motor diaphragm 24 while the gas to be diluted may be drawn into one side or the other of the pumping diaphragm 28. Thus my apparatus is capable of use to take in gas which may be available at a pressure not sufficiently high to operate the device. Under some circumstances, both the diluent gas and the gas to be diluted might be used to operate the device. My device may be used for instance on a compressed air line and connected to city gas at a pressure of one quarter of a pound per square inch.

50 The device will then operate to secure a proper admixture of the two gases. In many situations where compressed air is available, this compressed air may be used to dilute the gas for use in various heating processes and as the air is available at high pressures, the resultant product or finished gas is also available to correspondingly high pressure and can be conveniently piped about. It will be understood, therefore, that broadly considered, my device is capable of being operated by the pressure of one gas to dilute another gas and either the diluting gas or the gas to be diluted or both may be under pressure, which pressure might be utilized to operate the device.

It will also be seen that this device will operate 65 as a proportioning device to properly proportion one gas with relation to the other gas and it is within the purview of my invention to use this mechanism as a proportioning device.

In this case, the proportioning is accomplished 70 by using relatively different diameters for the two diaphragms used, namely diaphragm 24 and the diaphragm 28 and by causing the gas and diluent or both to be furnished under different relative pressures. In this case, the volumes of the gases 75 to be diluted or mixed are proportioned in a prac-

tically constant ratio controlled by the relative sizes or capacities of the two chambers making up the device and by the pressures under which the gas and the diluent are available at the device and the pressure under which they are admitted to the device. Obviously it is necessary that in addition to forcing in either the diluent or the gas, it is necessary to proportion the quantities of each in order to produce the desired quantity of produced or finished gas.

It is to be particularly noted that my apparatus comprises at least two narrow casings 23 and 27 and single diaphragms disposed within each of these casings and of such construction that the diaphragms may move the full depth of the casings and expel very nearly all of the gas or diluent on one or the other side of each diaphragm as the diaphragms reciprocate. My diaphragms have a relatively short travel distance because long travel is not practicable as the diaphragms are necessarily soft and pliable and when exposed to more pressure on one side than the other, will bag or stretch considerably. It is, therefore, necessary in order to obtain satisfactory efficiencies that the chambers in which the diaphragms are used must be so formed as to allow or compensate for this physical condition of the diaphragms. This is secured by making the chambers shallow and providing for relatively short strokes of the diaphragms and having the central portions of the diaphragms clamped between relatively large rigid disks so that the diaphragms displace all or nearly all the gas or diluent from the chambers on each stroke as by so doing, the efficiency of the apparatus is high and consequently the device can operate on lower gas pressure and/or deliver higher percentages of diluent per unit of gas passed through the device than would otherwise be the case. At the end of a stroke, therefore, the gas chamber contains only a small amount of gas between the diaphragm plates and the chamber wall, this gas being, of course, at discharge line pressure. Thus, when a diaphragm completes its stroke and reverses, it has virtually an empty gas chamber (or diluent chamber) as the volume of gas or diluent remaining in the chamber is relatively small.

I claim:—

1. A mechanism for forcing a gaseous diluent into a gas stream under pressure and fixedly proportioning the diluent to the gas including a rigid casing having a reciprocable diaphragm therein acting to divide the casing into two chambers, a valve chamber connected to the source of gas under pressure, a discharge pipe, a single valve in the valve chamber in one position connecting one of said chambers with gas under pressure and connecting the other chamber with said discharge pipe, and in the other position connecting the last-named chamber with the gas under pressure and the first-named chamber with the discharge pipe, a second rigid casing having therein a reciprocable diaphragm dividing the casing into two chambers, an operative connection between said piston-like elements, each chamber of the second named casing having an inlet port connected with a source of gas diluent, a valve for said port, an outlet valve, the outlet valve communicating with the discharge pipe from the first named valve chamber, and means operated by the first named piston-like element for alternately shifting said last named outlet valve in one direction or the other, including a lever, a pivoted arm connected to the last named valve, and means for causing a sudden movement of the last named valve to its 75

full position in one direction or the other after the lever has been shifted a predetermined distance.

2. A mechanism for forcing a gaseous diluent into a gas stream and proportioning the diluent to the gas in the stream, including a rigid casing having therein a single reciprocable diaphragm dividing the casing into two chambers, each chamber having a port, a valve casing connected to said ports and having a discharge pipe leading therefrom and having an inlet pipe leading thereto and connected to the source of gas under pressure, a single valve disposed within the valve casing and in one position connecting the inlet port of one of said chambers with the source of gas and the port of the other chamber with the discharge pipe, and in its other position connecting the port of the last named chamber with the inlet port and the inlet port of the first named chamber with the discharge pipe, a second rigid casing having therein a single reciprocable diaphragm dividing the casing into two chambers, each chamber having an inlet valve and an outlet valve, the outlet valves being connected to a common pipe with which the discharge pipe from the valve chamber connects, a connecting rod connecting the diaphragms of both of the chambers, and means for automatically operating said valve in the valve casing including a valve stem having stops, and oscillatable means operating between said stops and operatively connected to the connecting rod between the diaphragms.

3. A mechanism for forcing a gaseous diluent into a gas stream and proportioning the diluent to the gas in the stream, including a rigid casing

having therein a single reciprocable diaphragm dividing the casing into two chambers, each chamber having a port, a valve casing connected to said ports and having a discharge pipe leading therefrom and having an inlet pipe leading thereto and connected to the source of gas under pressure, a valve disposed within the valve casing and in one position connecting the inlet port of one of said chambers with the source of gas and the port of the other chamber with the discharge pipe, and in its other position connecting the port of the last named chamber with the inlet port and the inlet port of the first named chamber with the discharge pipe, a second rigid casing having therein a single reciprocable diaphragm dividing the casing into two chambers, each chamber having an inlet check valve and an outlet check valve, the outlet check valves being connected to a common pipe with which the discharge pipe from the valve chamber connects, a connecting rod connecting the diaphragms of both of the chambers, and means engaged with the connecting rod for automatically operating the valve in the valve casing, including a valve stem having stops, a lever pivoted at one end and operating between the stops and the valve stem, a second lever having a forked head engageable with the first named lever, the opposite end of the lever being operatively connected to the connecting rod between the diaphragms, and resilient means urging the first named lever from a medial position in one direction or the other.

HARRY CLEEVELY.
